UNITED STATES PATENT OFFICE.

EDWARD M. ANDERSON, OF JERSEY CITY, NEW JERSEY, ASSIGNOR TO ANDERSON & PRIGGE, INC., OF NEW YORK, N. Y., A CORPORATION OF NEW YORK.

NOTEBOOK HOLDER.

Application filed December 31, 1923. Serial No. 683,639.

To all whom it may concern:

Be it known that I, EDWARD M. ANDERSON, a citizen of the United States, and a resident of Jersey City, in the county of 5 Hudson and State of New Jersey, have invented new and useful Notebook Holders, of which the following is a specification.

The invention relates to note-book holders and the like, and comprises certain improvements in means for retaining and permitting removal of a book, for keeping the pages and marking a place in the book, and for bracing the parts to stand easel-fashion when desired. The improvements will now 10 be described in preferred embodiment and will be more particularly pointed out in the claims.

In the drawings forming part hereof:

Fig. 1 is a perspective view of the device 20 in position for transcribing notes, a portion of the book, which is shown in the holder, being torn away to reveal a part beneath;

Fig. 2 is an inner face view of a portion 25 of one of the boards and parts thereon, the page-retainer and book-mark arm being shown folded down and the book-retainer rod being shown in caught and in released positions by full and dotted lines, respectively;

Fig. 3 is a side elevation looking toward 30 the right in Fig. 2, the lower portions of the boards being broken away;

Fig. 4 is a side elevation looking to the left in Fig. 2; and

Fig. 5 is a fragmentary inner face view 35 of the board which stands in the rear when the holder is used as an easel support as shown in the drawings, this view illustrating more particularly the brace rod seen in 40 action in Figs. 1, 2 and 3 and here shown lying inactive upon the face of the board.

The holder comprises two boards or covers 1, 1^a, and a connecting part or binding 2 flexibly connected on either hand to the 45 boards.

A transverse plate 3 is eyelet-riveted to the inner face of the board 1 near its upper or binding end, the ends of this plate being bent up at right angles to the board to 50 present side ears 4, 4^a, which face each other. The ear 4 has a perforation at 5 and the ear 4^a has a slot 6. A transverse retainer rod 7 is loosely held at one end in the perforation 5, the end of the rod being enlarged at 8 to keep the rod from coming

out. The connection is such as to permit the rod to swing into and out of engagement at its other end with the slotted ear 4^a, as indicated by full and dotted lines in Fig. 2, and it is releasably caught in the latter ear by a movable catch 9, shown as consisting of a hooked plate pivoted at 10 to the ear, its limb 11 being adapted to remain by friction or gravity across the slot 6 to imprison the end of the rod therein. 60 By moving the catch away from the slot the end of the rod is released for insertion or removal of a book a. The rod is disposed across between the pages of the book, at the middle or elsewhere. Instead of the catch 65 shown, or a separate catch, other forms of means may be used for releasably keeping the rod 7 in the ear 4^a.

A second transverse rod 12 extends across 70 between the ears and is pivotally held therein. A connecting limb 13 is bent to extend substantially at right angles from this rod outside the ear 4, and the wire is bent again at the end of this limb to form an offset page-retainer and book-mark arm 14, which 75 extends transversely inward of the notebook holder.

When the stenographer is ready to take 80 notes the two boards are folded flat back to back, and the offset arm 14 is erected so that it stands above or beyond the binding 2. The pages as they are filled with notes are turned over the bar, which thus marks the starting point for transcribing notes. For 85 transcribing purposes, the holder is stood up like a tent, and the pages as they are transcribed are passed beneath the arm, as shown in Fig. 1. When the holder and book are closed, the arm is automatically folded down within the book, over the board 1, in 90 the position shown in Fig. 2. It is yieldingly held in its erect position by a lock conveniently afforded by a bump or projection 95 on the ear 4, arranged to cooperate with the limb 13. When the arm is erected the 100 limb is forced past this projection, either the wire or the plate, or both, yielding resiliently, and snapping into locking relation. The arm is as easily forced free of the lock when the book and holder are 105 closed.

The pivot rod 12 also performs the function of a back stop or abutment for the cover of the book which is retained by the adjacent rod 7.

In order to brace the boards to stand as an easel, a brace 16 is provided. This brace is simply a rod having its two ends 17, 17^a bent at right angles. Two metal tags 18, 18^a are riveted to the inner faces of the boards to present sockets 19, 19^a. Each tag is made of a piece of sheet metal, doubled upon itself, the two layers perforated for the eyelet rivets 20, and the connecting portion swelled 10 to form a tubular socket. The end 17^a is held in the socket of the tag 18^a on the cover 1 by reason of its extremity being enlarged, and can turn, and also slide endwise a short distance, in this socket. The other end 17 15 can be slipped in and out of the socket of the tag 18. The rod is sufficiently resilient and flexible to permit of this, or the end 17^a can be made to have a greater extent of sliding movement in the socket 19^a if desired. 20 When the brace is not in use it lies flat against the face of the board 1^a.

Means are also provided whereby the stenographer can brace the boards by means of her pencil. For this purpose two eyelets 21 25 of appropriate size are shown in the margins of the two boards, preferably at the opposite side from the hinged brace just described. Such eyes afford means both for the bracing of the holder and for holding 30 the pencil *b*, and may be used in conjunction with an attached brace or not as desired.

It will be understood that I do not necessarily limit myself to the precise forms shown herein.

35 What I claim as new is:

1. In a note-book holder having a board, a plate secured to the face of the board to present side ears facing each other, one of said ears having a perforation and the other 40 ear having a slot, a retainer rod which extends substantially across the board, the rod being passed loosely through said perforation and having a retaining head at one end, and means for catching the other end in 45 said slot, substantially as set forth.

2. In a note-book holder having a board, a plate secured to the face of the board to present side ears, a retainer rod which extends substantially across the board, the rod 50 being loosely held in one of said ears, and a movable catch on the other ear for releasably engaging the rod, substantially as set forth.

3. In a note-book holder having a board, 55 a plate secured to the face of the board to present side ears, a retaining device on said

ears to enter a note-book, and a transverse rod pivoted in the ears above and adjacent the retaining device and carrying an offset page-keeper and book-mark arm, substantially as set forth. 60

4. In a note-book holder having a board, a plate secured to the face of the board to present side ears, a transverse retainer rod loosely held in the ear at one side and releasably held in the ear at the other side, and a second transverse rod pivoted in the ears above and adjacent the retainer rod and carrying an offset page-keeper and book-mark arm, substantially as set forth. 65

5. In a note-book holder having a board, a plate secured to the face of said board, and an offset page-keeper and book-mark arm having a pivotal mounting on said plate so that the arm can be erected or 70 folded down over the board, substantially as set forth.

6. In a note-book holder having a board, a plate secured to the face of said board, and an offset page-keeper and book-mark arm having a pivotal mounting on said plate so that the arm can be erected or folded down over the board, with a lock past which the arm is forced yieldingly to erect it, substantially as set forth. 75

7. In a note-book holder having a board, a plate secured to the face of said board, a transverse pivot rod rotatably mounted in said plate, a connecting limb substantially at right angles to said pivot rod and a page-keeper and book-mark arm extending inward from said connecting limb, together with a yielding-lock projection on the plate cooperative with said connecting limb, substantially as set forth. 80

8. The combination with a pair of connected boards, of means comprising suitable eyes on the boards for bracing the boards to stand easel-fashion by means of a pencil or the like passed through the eyes, substantially as set forth. 85

9. The combination with a pair of connected boards, of two tags on the faces of the respective boards, each tag presenting a socket, and a brace consisting of a rod having its two ends bent at right angles, one of said ends being pivotally held in one of the sockets and the other end adapted to slip in and out of the other socket, substantially as set forth. 100

EDWARD M. ANDERSON.
